UNITED STATES PATENT OFFICE.

JOSEPH N. NOYER, OF GOULD CITY, WASHINGTON.

WRENCH.

SPECIFICATION forming part of Letters Patent No. 757,764, dated April 19, 1904.

Application filed December 17, 1903. Serial No. 185,540. (No model.)

To all whom it may concern:

Be it known that I, JOSEPH N. NOYER, a citizen of the United States, residing at Gould City, in the county of Garfield, State of Washington, have invented certain new and useful Improvements in Wrenches; and I do hereby declare the following to be a full, clear, and exact description of the invention, such as will enable others skilled in the art to which it app- 10 pertains to make and use the same.

This invention relates to wrenches in general, and more particularly to the class of ratchet-wrenches, the object of the invention being to provide a cheap and simple form of wrench which may be easily and quickly ad- 15 justed to engage bodies of different sizes and in which the parts may be readily adjusted to feed the head rotatably in either direction as the handle or lever is oscillated.

20 Other objects and advantages of the invention will be understood from the following description.

In the drawings forming a portion of this specification, and in which like numerals of reference indicate similar parts in the several views, Figure 1 is a side elevation showing a wrench embodying the present invention. Fig. 2 is a section through the ratchet portion of the head of the wrench and the head of the 25 pawl engaged therewith, other portions being shown in elevation. Fig. 3 is a central longitudinal section through the head and a portion of the handle at right angles to the plane of Fig. 2. Fig. 4 is a section taken longitudinally through the head in a plane between the jaws thereof, a portion of the stem of the head being in plan. Fig. 5 is a detail view of the pawl.

Referring now to the drawings, the present 30 wrench comprises a head 10, having upon one face a rigid jaw 11, which projects at right angles thereto, and having projecting from the center of its opposite face a cylindrical stem 12, said head being substantially cylindrical 45 at its main or central portion. The curved face of the head directly adjacent to the stem 12 is provided with ratchet-teeth 13 for a purpose to be presently explained.

Formed diametrically through the head 10, 50 between the ratchet-teeth 13 and the jaw 11,

is a passage 14, which is so located as to pass below the base of the jaw 11, and between said jaw and the diametrically opposite point of the periphery of the head the end face of the head is slotted, as shown at 15, said slot com- 55 municating with the passage 14.

Cooperating with the jaw 11 is a movable jaw 16, having a stem 17, which is passed through the passage 14, the base of the jaw 16 being slightly narrowed and lying in the slot 15, so that as the stem 17 is reciprocated in the passage 14 the jaw 16 will be moved toward and away from the jaw 11. To thus reciprocate the stem 17, its ends portion opposite to the jaw 16 is threaded and is engaged 60 by a nut 18, having a base-flange 19, that engages a groove 20 in the lug 21 at the outer side of the base of the jaw 11. As the nut 18 is rotated in one direction the stem is drawn through the passage 14 with the jaw 16 to- 70 ward the jaw 11, and when the nut is rotated in the opposite direction the stem 17 is forced through the passage in the opposite direction to move the jaw 16 from the jaw 11. During the last-named movement of the stem the nut 75 18 is held against movement away from the head 10 by engagement of the flange 19 in the groove or channel 20.

A handle 22 is provided and has at one end a grip 23 and at the other end an enlargement 80 24, having a perforation 25 therethrough which forms a bearing for the stem 12 of the head 10, a cotter-pin 26 being engaged through the end of the stem for the well-known purpose. 85

A pawl carrier or guide is provided and consists of a housing 27, having a longitudinal cylindrical passage 28 therethrough, the carrier or guide being slotted longitudinally at one end, as shown at 29, and having a longitudinal extension 30 at said end at one side of the slot, this extension being designed for engagement therethrough of a screw 31, which is engaged also through the handle 22 and holds this end of the carrier or guide securely 90 to the handle. The opposite end of the carrier or guide 27 lies in close proximity to the periphery of the toothed portion of the head 10, and at this end of the guide is a lip 32, which engages in a peripheral groove 33 in 95 100

the head, this engagement serving to hold the corresponding end of the guide against movement away from the handle 22. The end of the passage 28 farthest from the head 10 is 5 slightly reduced in diameter, as shown at 34, and through said passage or into said passage is passed a substantially cylindrical pawl 35, having at one end a slightly-enlarged head 36, which is beveled at one side, as shown at 37. 10 Upon the pawl 35 is disposed a helical spring 38, one end of which rests against the head 36, while the other end rests against the shoulder 39, formed by the reduction of the diameter of the passage 28. This helical spring 15 serves to hold the head 36 with its beveled face normally and yieldably projected from the passage 28 and into engagement with the teeth 13. A pin 40 is engaged through the pawl 35 transversely at the opposite end from 20 the head 36 and lies in the slot 29, from which it projects. The pin serves to hold the pawl against rotation, and when the pin 40 is in position to project from one side of the guide 27 the bevel 37 of the head 36 is at one side of 25 the wrench, while when the pin projects from the other side of the guide said face is at the opposite side of the wrench. With this construction it will be seen that when the head is held and the handle 22 is moved upon the stem 30 12 in one direction the pawl 35 will engage one of the teeth 13 and the head will then be moved with the handle, and when the handle is moved in the opposite direction the beveled face 37 will engage and ride over the teeth successively, so that the head will not be rotated. If 35 the pawl be rotated in the guide 27 through one hundred and eighty degrees, the handle will urge the head in the opposite direction when oscillated, it being only necessary to grasp the 40 pin 40 and draw the pawl rearwardly against the action of the spring 38 to permit of shifting of it from one position to the other.

It will be understood that in practice modifications of the specific construction shown may be made and any suitable materials and proportions may be used for the various parts without departing from the spirit of the invention. 45

What is claimed is—

1. A wrench comprising a handle, a head provided with jaws and having a ratchet - wheel and a peripheral groove adjacent to the latter, a guide attached at one end to the handle and having a lip at its opposite end engaged in said groove, said guide having a longitudinal passage therethrough and a transverse slot in its end opposite to the head, a pawl slidably mounted in said passage and having its end adjacent to the head beveled at one side and adapted for engagement with the ratchet-wheel, means for holding the pawl yieldably in engagement with the ratchet - wheel, and a pin engaged transversely through the pawl and lying in said slot, said pawl being movable with the pin from the slot and rotatable when the pin is thus disengaged. 55 60

2. A wrench comprising a head having a fixed jaw and a transverse passage passing beneath the jaw, said head having a slot in its face from which the jaw projects and communicating with the passage, a second jaw having a threaded stem slidably engaged in the passage, the second jaw projecting through said slot, a lug upon the face of the fixed jaw opposite to the second jaw and having a groove therein 75 and a feeding-nut engaged with said threaded stem and having a peripheral base-flange engaging said groove. 70

In testimony whereof I affix my signature in presence of two witnesses.

JOSEPH N. NOYER.
